UNITED STATES PATENT OFFICE.

FREDERICK SANDERSON, OF CHICAGO, ILLINOIS.

DOOR-BELL.

SPECIFICATION forming part of Letters Patent No. 432,285, dated July 15, 1890.

Application filed February 26, 1890. Serial No. 341,884. (No model.)

To all whom it may concern:

Be it known that I, FREDERICK SANDERSON, a citizen of the United States, residing at Chicago, in the county of Cook and State of Illinois, have invented a new and useful Improvement in Door-Bells, of which the following is a specification.

My invention relates to that class of door-bells which are applicable to either doors or door-jambs, or other similar situations, without making any radical change in the operative mechanism.

One object of my invention is to arrange the pivotal center of an elbow-lever which 15 operates the hammer in relation to the pivotal center of the elbow-lever's connection with the push-button so that a very slight push upon the push-button will cause the hammer to give two distinct strikes upon the bell.

Another object is to provide two arms to the hammer-operating elbow-lever, which arms contact with stops on the frame to which the elbow-lever is pivoted, for the purpose of 20 limiting the motion of said elbow-lever for 25 the purpose of causing a quick retraction of the hammer from the bell after it has struck.

Another object is to so connect the push-button and the lever which operates the hammer that the connection will be in alignment 30 by the introduction of a bifurcated pitman, which permits the hammer to vibrate vertically within the space between the two arms of the bifurcation of said pitman.

Another object is to provide a self-centering part to the side of the apparatus where it contacts with the door, which also acts as a guide for part of the operative mechanism, as will be fully explained hereinafter.

I attain these objects by the mechanism 40 illustrated in the accompanying drawings, in which—

Figure 1 is a vertical center section on line A B, Fig. 2, with operative mechanism in elevation. Fig. 2 is a horizontal center section 45 on line C D, Fig. 1, with operative mechanism and the frame to which the bell is attached in elevation. Fig. 3 is a detached top view of the frame or standard, to the outer end of which the bell is secured, and into which the 50 lever for operating the hammer is pivoted. Fig. 4 is a detached side view of the elbow-lever for operating the hammer, together with

its spring-arm with hammer attached. Fig. 5 is a perspective rear view of the base by which all the apparatus of the bell is attached to 55 the door. Fig. 5 also shows self-centering device and guide for button-rod. Fig. 6 shows respectively side and top detached views of bifurcated connection between push-button rod and hammer-operating elbow-lever. Fig. 60 7 shows part of the door with hole and position of self-centering device, as will be described.

Similar letters refer to like parts in the several views.

E is a bell, which is secured to the end of frame F by means of a screw a. The frame F, Fig. 3, is secured to the base-plate G at b. The plate G is circular in shape, Fig. 5, and in Figs. 1, 2, and 3 is shown a flange c around 70 its outer edge. This plate G is provided with screw-holes d, Fig. 5, which are occupied with wood-screws for firmly attaching it to its proper position on a door or any other place desired. The head of the frame F is slotted 75 out near the end at e, and into this slot is pivoted an elbow-lever H upon a pin f, Figs. 1 and 2. The lever H vibrates in a vertical direction, and it is provided with two projections g and h, which contact with shoulders i 80 and j on the head of the frame F, thus limiting the movement of the elbow-lever H. One arm of the elbow-lever H is formed by the spring-rod k, which has the hammer I secured to its outer end. To the short arm of the elbow-lever H is pivotally attached by a pin l, 85 Figs. 1 and 2, the bifurcated connection m, Fig. 6, and the opposite end of the said connection m is held in position and slides in notches n cut into the sides of the slot J, which 90 slot is cut through the plate G, Figs. 2 and 5.

The push-button K is of the usual form, with shoulder, and operates in the usual escutcheon K'. To the inner end of the push-button is attached a small rod o, whose opposite end is guided and slides in the hole p in the U-shaped part L, Fig. 5, which is at the center of the rear side of the plate G. This U-shaped part serves also another purpose. When the door-bell is to be attached, a hole 95 N is bored through the door. The dimensions of the part L from any one of its corners to the diagonally-opposite corner is slightly larger than the diameter of the hole N, so that the

part L is forced into the hole N, and thus centers the plate G, together with the attached operative mechanism, as shown by Fig. 7. Thus but few screws are required to secure the plate G to a door, and it is prevented from even slightly changing its position when once in place.

In operation one push inward upon the push-button K causes the rod o to contact against the end of the bifurcated connection m, the connection m being pivoted to the elbow-lever H at l in such a relative position to the pin f that when the several operative parts of the apparatus are in normal position when at rest the two centers f and l are almost in line with a center line from the pivot f to the rod o and the push-button, and for this reason a very small inward movement of the push-button will cause the elbow-lever to turn on its pin f, and through the medium of its spring-arm k cause the hammer I to quickly rise and strike the inside top of the bell, as shown by the dotted lines, Fig. 1. As soon as the pressure is removed from the push-button K, the hammer I, by its own weight, falls and strikes a second blow upon the inside of the bell at the bottom, Fig. 1. The hammer I and its spring-arm k in both their upward and downward strokes pass between the bifurcations of the connection m, so that pressure upon the push-button is transmitted centrally and with no side draft to the hammer-operating lever H. The hammer is instantly retracted from the bell after it has struck by means of the spring-arm k. The elbow-lever H does not vibrate enough to throw the hammer against the bell at either the top or bottom stroke; but when the ends of the arms g and h contact with the shoulders i and j, limiting the stroke of the elbow-lever, the momentum of the hammer I springs the arm k enough to cause the hammer to contact with the bell; but as soon as the blow is delivered the bent spring-arm k instantly withdraws the hammer, when it stands at the top or bottom of its stroke in the relative position shown in Fig. 1. The gravity of the hammer I, acting upon the elbow-lever H, through the medium of the connection m and rod o, always holds the push-button outward with its shoulder in contact with the escutcheon K'.

It will be noticed in Fig. 1 that the pivotal center f of lever H and the pivotal center l of the end of bifurcated connection m are almost in line with the longitudinal center of the push-button rod o when the mechanism is at rest, and on this account the elbow-lever

H starts a little hard at first pressure upon the push-button, but when started it turns suddenly upon its pivotal pin f, causing the hammer I to deliver a quick upward blow upon the bell, the natural result of which is that the person pushing the button, after hearing the sound of the bell, will instantly release the pressure, when the gravity of the hammer descending will cause the second blow on the bottom of the bell. Thus a quick succession of blows can be delivered on the bell by means of this simple arrangement of mechanism.

What I claim as my invention, and desire to secure by Letters Patent, is—

1. In a door-bell, the elbow-lever H, pivoted in slot e of frame F, spring-arm k, attached to said lever H, hammer I, attached to said arm k, bifurcated connection m, pivoted at l to said elbow-lever H, spring-arm k, and hammer I, operating vertically between the bifurcations of said connection m, in the manner and for the purpose substantially as shown 80 and described.

2. In a door-bell, the elbow hammer-arm operating lever H, provided with stop-arms g and h, said elbow-lever H being limited in its motion on pin f by said stop-arms g and h 85 contacting with shoulders i and j, for the purpose hereinbefore described.

3. In a door-bell, the bifurcated connection m, pivoted at one end to elbow-lever H and supported and operating at the opposite end 90 in notches n in the sides of slot J of base-plate G, one end of rod O contacting with the end of connection m, as shown, said rod O having attached at its opposite end a push-button K, all for the purpose of connecting 95 push-button K with and operating elbow-lever H by pressure on said push-button K.

4. In a door-bell, the frame F, provided with contact shoulders i and j, elbow-lever H, having arms g and h, which contact with said shoulders i and j and limit motion of said elbow-lever H, spring-arm k, attached to said lever H, said spring-arm k having hammer I attached to its outer end, bifurcated connection m, pivotally attached to elbow-lever H at 105 l, hammer I, and spring-arm k, operating vertically between the bifurcations of connection m, in combination with push-button K and its rod o, as described.
